UNITED STATES PATENT OFFICE.

HENRY L. PITMAN, OF ELIZABETH, NEW JERSEY.

WINDING MECHANISM.

Application filed January 2, 1919. Serial No. 269,311.

To all whom it may concern:

Be it known that I, HENRY L. PITMAN, a citizen of the United States, residing in Elizabeth, in the county of Union and State 5 of New Jersey, have invented certain new and useful Improvements in Winding Mechanism, of which the following is a specification.

This invention relates to spring motors 10 for driving the turn tables which carry the records in phonographs, and embodies improvements upon my pending applications 149,855 and 193,138.

Owing to the great length of the multiple-helix spring disclosed in said applications, 15 its tension increases very gradually as it winds, and hence fails to give adequate warning that it has been sufficiently rewound, and therefore there is liability of the spring 20 becoming overwound and perhaps injured. One of the objects of the invention is to prevent overwinding of a spring whose winding and unwinding motions progress in the same direction as is customary in phonographs. 25 To attain this object, there is provided a device which is effective at any stage of unwinding, and which is preferably dependent upon the condition of the spring itself, for preventing overwinding. That is, the spring 30 is self-locking, or provided with a lock which may be brought automatically into play for checking overwinding. In the preferred form of this feature, the inner helix of the spring, during the rewinding operation, contracts upon a core which is normally idle, 35 but which, when gripped by the said helix, is caused to turn therewith, and bring into use a stop by swinging the same into engagement with a ratchet wheel connected to 40 the winding devices, to check the same.

Other features and advantages will hereinafter appear.

In the accompanying drawings,

Figure 1 is a part-sectional side elevation 45 of the floor of a phonograph, with a spring motor secured to the under side thereof, and embodying the present improvements in one form.

Figure 2 is a bottom plan of the motor 50 and appurtenances.

Figure 3 is an enlarged diagrammatic view illustrating the released position of the overwind-check device; and also showing in dotted lines the released position of the back 55 check for the motor spring.

Figure 4 is a view similar to Figure 3,

but showing the device locked against further winding.

Figure 4^a is a sectional view of a driving collar to be placed upon one end of the 60 winding shaft, as seen at Figure 5.

Figure 5 is a sectional longitudinal view of the winding shaft and its appurtenances; said shaft shown detached from the stub-shaft or winding head to which it is to be 65 coupled and by which it is to be driven.

Figure 6 is a friction washer which cooperates with the locking pinion seen at Figure 7.

Figure 7 is an enlarged view to illustrate 70 the tensioned motor spring as under control of the lock which prevents it from unwinding.

Figure 8 is a view of the ratchet wheel which is attached to the winding shaft to be 75 used in locking the same against overwinding.

Figure 9 is a detail view of one end of the spring-winding shaft upon which is to be fitted the overwind-check ratchet wheel seen 80 at Figure 8.

Figure 10 is a sectional elevation to illustrate the frictional connection between the brake arm and the regulating arm, to permit relative adjustment therebetween, while 85 enabling the regulating arm to control the operation of the brake arm.

Figure 11 is a perspective view of one end of the winding shaft, opposite from the end seen at Figure 9.

Figure 12 is a perspective view of an arm which limits the throw of the locking pinion seen at Figure 7, when said pinion is moved to releasing position.

Figure 13 is a perspective view showing 95 the parts detached which are seen assembled at Figure 10.

Figure 14 is a perspective view of a coupling collar which is seen at Figure 5 on the left-hand end of the spring-winding 100 shaft.

As usual in the phonograph, the record is carried upon a turn table which is mounted upon a central vertical shaft 20, extending up through an opening 21 in a bed or plate 105 22, and supported at its upper end in a bearing 23 and at its lower end in a step or bearing 24. This shaft 20 is revolved by a spring-motor barrel 25, which turns about a horizontal shaft 26, and has at one end a gear 27 110 to drive a pinion 28, which is mounted upon one end of a horizontal shaft 29, the latter

carrying a spiral gear 30 to drive a spiral pinion 31 on said turn-table shaft 20.

To wind the spring, a crank 32 is screwed upon a threaded end of crank shaft 33, which projects from the framework and carries a driving pinion 34 to mesh with a winding gear 35, which is preferably pinned at 37 to a stub shaft 38, which is connected to detachable shaft 26 by a tongue and groove coupling 39, 40.

At Figure 7, the driving pinion 34 and the winding gear 35 are shown in mesh with an idle pinion 41, so that all three gears in the train are locked; hence, the shaft 26 cannot be rotated reversely by the spring. The tension of the spring is in a direction opposite from that indicated by the arrow at Figure 7. To wind the spring, the crank 32 is turned in the direction shown by the arrows at Figures 1 and 7. This turns the driving pinion 34 and thereby revolves the winding gear 35, as shown by the arrows. As gear 35 starts, it carries the locking pinion 41 bodily away from the position at Figure 7, to the position at Figure 1, where it cannot interfere with the rotation of the driving pinion 34. The locking pinion 41 remains in this released position, revolving idly, during the ensuing winding of the spring motor 30 by the crank 32. For this releasing movement, the pinion 41 is pivoted upon an idle arm 42, which is pivoted loosely on the stub shaft 38. A friction washer 43 always opposes the independent rotation of the locking pinion 41, said washer for this purpose being interposed between said pinion 41 and the arm 42, Figure 5. The pinion 41 is pivoted upon a shoulder screw 44 threaded into said arm. It will be perceived that the initial winding movement of the gear 35 carries the pinion 41 and arm 42 from the Figure 7 position to the Figure 1 position, inasmuch as it is easier for the arm and pinion to swing away from the pinion 34 than it is for the pinion 41 to turn upon its own axis 44, owing to the presence of friction washer 43. The teeth of the pinions 34 and 41 may be beveled to give sufficient clearance during this unlocking operation. The releasing movement of pinion 41 and arm 42 may be limited by a stop arm 45, also pivoted loosely upon the stub shaft 38 and having a finger 46 to catch over the pinion arm 42, said arm 45 being arrested by striking the hub of the crank, as at Figure 3. During the winding operation, the locking pinion 41 revolves idly and noiselessly. As soon as crank 32 is released, the motor spring reacts upon the winding gear 35, driving the same in the opposite direction from the arrow seen in Figure 1, and thereby swinging the locking pinion 41 again into mesh with the winding pinion 34, as at Figure 7, so that the train becomes relocked, and further unwinding of the spring is prevented.

The spring 47 illustrated is of the multiple master helix construction disclosed in said applications, and comprises a central helix 48, through which the winding shaft 26 extends. The outer helix is hooked over a headed supporting stud 49 projecting inwardly from the driving gear 27; the last whorl of this helix being also confined within a supporting hook 50, which also projects inwardly from the gear 27. It is noted at this point that this gear 27 may form the head of casing or barrel 25, which is in the form of a long cylinder secured at one end by screws 52 to said head, and at the opposite end having a head 53 which is loosely centered upon the main or winding shaft 26, or upon a core (or sleeve) 54 which is loose upon said shaft. The end of the innermost helix 48 is hooked under the head of a screw 55, threaded into a collar 56 upon the shaft 26. When said collar and shaft are rotated by the crank 32, as already explained, said inner helix 48 is wound up, the winding motion being communicated to the outer helices. This collar 56 has a reduced inner end 57, upon which fit the end whorls of the helix 48; the opposite end of the helix surrounding the loose core 54 and supportable thereby.

The end of the shaft 26 is reduced at 58 to receive collar 56, 57, which abuts against the shoulder at the end of the reduced portion of the shaft. The tip of this reduced end 58 is still further reduced to form a centering nipple 59, to fit into a socket 60 in the revoluble stub shaft 38, which may remain permanently in the machine while the shaft 26 with the spring 47 is being assembled or withdrawn. The tongue or flattened portion 39 of the reduced section 58 of the shaft fits in the transverse groove of a head 61 on stub shaft 38. The disk 62, which may be formed or fixed upon the collar 56, may serve to take the end thrust of certain of the helices, so that there will not be friction between said helices and the inner face of the gear 27, which is loosely pivoted upon a hub 63 formed upon the collar 56. The transverse groove 40 extends entirely across the large head 61, and receives the divisions of a tongue 64 which is formed upon the outer end of the collar 56, so that said collar is directly driven by the stub shaft 38, together with said inner helix 48.

The right-hand end of the winding shaft 26, at Figure 5, is detachably mounted, there being provided for this purpose a removable stud 65, secured by a set screw 66 in the framework 67, and having on its inner end a nipple 68, which serves as a bearing for said shaft 26, this shaft having in its end a bore 69 to fit upon said nipple. By loosening the screw 66 and withdrawing the stud 65, the shaft 26, together with the spring 47

barrel 25, may be moved endwise and tilted up and detached from the head 61 of the stud shaft 38, whereupon the barrel 25 may be withdrawn.

5 The loose core or sleeve 54 is also used in preventing overwinding of the spring motor. This core remains stationary upon the revolving shaft 26 during the winding of the spring; the core being held against 10 rotation by an arm 70 having a spring 71; said spring and arm being pivoted upon a stud 72, secured by a set screw 73; and said arm and spring may be confined upon the inner projecting end of the stud by means 15 of washer 74 and screw 75. One end of the spring may bear against a stud 76, and the other end against a portion which is rigid with arm 70. The power of the spring 71 is sufficient to hold the arm 70 against the 20 tendency of the sleeve 54 to revolve with the shaft 26 during the winding operation; but, when the winding proceeds to such an extent that the whorls of the innermost helix 48 contract so much as to grip the sleeve 54, 25 as shown at Figure 4 and in dotted lines at Figure 5, the sleeve is caused to rotate by the friction of the whorls thereon; this being the end of the helix 48 which is opposite from the hooked end at 55 and which 30 is free to tighten upon the core or sleeve 54. The opposite ends of said helix are relatively revoluble to an extent to permit this contraction and gripping. The core 54, being thus automatically rotated, pushes the 35 arm 70 to the left from the position at Figure 3 to the position at Figure 4, to bring dog or stop 77 into the path of one of the teeth of ratchet wheel 78, and thereby arrest the shaft 26 and stop the winding. 40 It is noted that said ratchet or stop wheel 78 may have an oblong central opening 79 to fit upon a key portion 80 formed upon the right-hand end of the winding shaft 26, so that the ratchet wheel and shaft must 45 revolve together, and danger of injury is avoided. Hence the spring is self-locking against overwinding. The arrest of the winding depends upon the condition of the spring 47 itself. In other words, when the 50 spring has been tensioned to an extent to cause the innermost whorls thereof to bind upon the sleeve 54, the stop 77 is automatically thrown into position to arrest the winding. This may happen at any stage in 55 the rotation of the spring barrel 25. The diameter of the core 54 is such as to be gripped by the helix whorls before the contraction in diameter of the several helices has proceeded far enough to enable any 60 helix to contact with the next inner helix. In other words, a clearance is always left between the several helices, to prevent over-tensioning of the spring, and to prevent the whorls of the helices from noisily scraping 65 over one another, or slipping between one

another, and to permit free flow of lubricant between adjacent whorls. The arm 70 may work in a peripheral slot 81 formed in the core 54 near its end, and thereby prevent longitudinal displacement of the core; 70 while one end of the slot forms a shoulder to engage the arm 70 for throwing in the stop, as already explained.

As soon as the winding is arrested, the operator releases the crank 32, and the 75 motor spring reacts as hereinbefore explained, the winding shaft 26 turning backwardly until the locking pinion 41 remeshes with the driving pinion 34, as at Figure 7; and, during this backward rotation of shaft 80 26, the sleeve 54 may turn therewith by reason of the engagement of the spring-pressed arm 70 with the shoulder on the sleeve, as well as by the grip of the whorls 48 upon the sleeve. The spring 71 will, therefore, 85 swing the stop 77 out of the path of the ratchet 78 as at Figure 3, so as to release the ratchet wheel and shaft for a subsequent winding operation; a finger 81^a on the stop engaging a pin 81^b to arrest the releasing 90 movement of the stop.

The device for governing the speed of rotation of the usual turn table on shaft 20 may comprise a gear 83 on said shaft, to mesh with a pinion 84, to which is fixed a 95 spiral gear 85, which meshes with a worm 86, the latter carried upon a shaft 87, which is thus caused to revolve at high speed, thereby separating centrifugal weights 88 which are carried upon flexible arms 89, whereby 100 the arms are shortened, thereby pulling a brake disk 90 against a brake arm 91, and so controlling the speed of rotation of the disk 90 and hence of the turn table. In order to set the brake arm 91 to regulate the 105 speed as required, there may be used a controller comprising a button 92 fixed upon the upper end of a vertical shaft 93, which has a bearing in a boss 94 secured to the base plate 22; said shaft carrying at its 110 lower end an arm 95, having a pin 96 to engage a slot 97 in a long regulating arm 98, so that rotation of the button will vibrate said regulating arm 98. The latter has a connection with the brake arm 91, and accordingly controls or sets the latter. The controller may be provided with an index 99 to co-operate with scale 100, to determine the speed of operation; and a stop 101 may be used with said index and button, so that 115 in starting the motor by turning the button, the index may be arrested by said stop and thereby the brake arm 91 may be mechanically set to a point which will give the desired speed of the turn table.

The frictional connection between the regulating arm 98 and the brake arm 91 will now be explained, the parts being shown separated at Figure 13 and assembled at Figure 10. Said regulating arm 98 has 120

fixed thereto a hub section or portion 102 in the form of a plate pivoted to fit upon a post or stud in the form of a shoulder 103, formed on a screw 104. The two parts 102, 98 are connected by a screw 105, which holds the part 98 down in a fitted seat formed by sides 106 stuck up from the plate 102; so that the parts 98 and 102 are detachably fixed together. The brake arm 91 is pivoted upon the same stud 103; and a compression spring 107 surrounds the stud and presses the arm plate 102 against the hub of the brake arm 91 with great force, so they are bound together and ordinarily move together. A friction plate or washer 108 is inserted between the head 109 of the stud and the brake arm 91, and doubles the effect of the frictional connection between the lever 98 and the brake arm 91, since this friction plate has a tongue 110 extending to and fitting between the sides 106 of the lever plate 102, so that the washer must turn with said regulating arm 98, while it may move up or down independently of 98. Thus relative motion between the brake arm 91 and said regulating arm 98 is opposed by a friction upon both the top and bottom surfaces of arm 91. The resistance here is too strong to be overcome by the pressure of the brake disk 90 against the brake arm 91.

The movement of brake arm 91 in one direction, that is, to the right at Figure 2, is limited by its engagement with the friction-governing disk 90; and its motion in the opposite direction, or towards the left at Figure 2, is governed by an end of a screw 111 striking a fixed stop 112, said screw forming an adjustable stop to regulate the extent of throw of the brake arm 91. Thus the regulating arm 98 may have considerable vibration upon its pivot 103 while maintaining a fixed relation to the brake arm 91; and this vibration is sufficient to accommodate the purpose of the motor-starting and speed-regulating button 92. But in adapting the apparatus to different types of phonographs, the lever 98 may be swung independently, as indicated in dotted lines in Figure 2, to accommodate different positions in which the controller (92) may be located in the machine during the process of manufacture; this relative shifting being permitted by the frictional connection between the parts 98 and 91. Wherever said arm 98 may be thus swung, it will thereafter perform the function of controlling the arm 91 already explained. Thus the arm 98 adapts the motor mechanism to different types of phonographs, and is inexpensive to make, and readily detachable and adjustable to accommodate the controller, as it does not need to be bent or distorted in order to accommodate the mechanism to different phonographs.

65 Variations may be resorted to within the

scope of the invention, and portions of the improvements may be used without others.

Having thus described my invention, I claim:

1. The combination of a spring comprising 70 a coil, means to wind said spring, a device within said coil and normally stationary while the coil turns, but gripped and turned by the coil as the latter decreases in diameter when tensioned, and a stop brought 75 into play by said device when turned by said coil, for arresting the winding of the spring.

2. The combination of a spring comprising 80 a helix, winding means connected to one end of said helix, a core within said helix and normally stationary while the helix turns, but gripped and turned by the helix at the other end thereof as the spring contracts under tension, and a stop brought 85 into play by said core for arresting the winding of the spring.

3. In a spring motor, the combination of 90 a spring comprising a helix, a revoluble core within the helix, means to wind the spring, means to hold said core stationary during the winding of the spring, said core engageable and rotatable by the helix as the latter contracts upon winding thereof, and a stop brought into play by said core for arresting the winding. 95

4. In a spring motor, the combination of 100 a spring comprising a helix, a revoluble core within the helix, means to wind the spring, means to hold said core stationary during the winding of the spring, said core engageable and rotatable by the helix as the latter contracts upon winding thereof, a stop brought into play by said core for arresting the winding, and a spring to restore 105 said stop device to normal released position.

5. In a spring motor, the combination of 110 a spring comprising a helix, a revoluble core within the helix, means to wind the spring, means to hold said core stationary during the winding of the spring, said core engageable and rotatable by the helix as the latter contracts upon winding thereof, said winding means including a winding shaft concentric with said core and having a ratchet 115 wheel, and a stop normally released but movable by said core into engagement with said ratchet wheel to stop the winding.

6. In a spring motor, the combination of 120 a spring comprising a helix, a revoluble core within the helix, means to wind the spring, means to hold said core stationary during the winding of the spring, said core engageable and rotatable by the helix as the latter contracts upon winding thereof, said winding means including a winding shaft concentric with said core and having a ratchet wheel, a stop normally released but movable 125 by said core into engagement with said ratchet wheel to stop the winding, and a 130

spring to return said stop to normal released position, together with said core.

7. In a spring motor, the combination of a spring comprising a helix, a revoluble core 5 within the helix, a winding shaft within said helix, a ratchet wheel mounted upon said shaft, said core being in the form of a loose sleeve upon said shaft and having a peripheral slot, and a pivoted stop, said stop having an operating arm within said slot, to be engaged by the core as the latter is turned by the contracting helix, to move said stop into engagement with said ratchet wheel.

8. In a spring motor, the combination of 15 a spring comprising inner and outer helices, a revoluble core within the inner helix, means to wind the spring, means to hold said core stationary during the winding of the spring, said core engageable and rotatable 20 by the inner helix as the latter contracts upon winding thereof, and a stop brought into play by said core for arresting the winding.

9. The combination of a multiple helix 25 single wire continuous spring, a winding shaft for said spring, said shaft extending centrally through the spring, a stop normally released, said shaft carrying thereon a stop member, and spring operated means 30 brought automatically into play at the conclusion of the winding operation, for effecting engagement between said stop member and said normally released stop, to prevent overwinding.

35 10. The combination of a multiple helix single wire continuous spring, a winding shaft for said spring, said shaft extending centrally through the spring, a stop normally released, said shaft carrying thereon 40 a stop member, and means dependent upon the tensioned condition of the spring, for effecting engagement between said stop member and said released stop to prevent overwinding.

45 11. The combination with a revoluble spring barrel, of a single wire continuous motor spring comprising helical coils nested one within another within said barrel, one end of said spring connected to said barrel to 50 drive the same, a central shaft upon which said barrel is loosely mounted, the other end of said spring being connected to said central shaft to enable the shaft to wind the spring, a stop mechanism normally ineffective to 55 control said shaft, and means dependent upon the tensioned condition of the spring

for bringing said stop mechanism into play to stop said shaft, to prevent overwinding.

12. The combination with a revoluble 60 spring barrel, of a motor spring comprising helical coils nested one within another within said barrel, one end of said spring connected to said barrel to drive the same, a central shaft upon which said barrel is loosely mounted, the other end of said spring 65 being connected to said central shaft to enable the shaft to wind the spring, a stop mechanism normally ineffective to control said shaft, and means operating between said shaft and a contracting portion of said 70 spring, for automatically arresting the winding operation of said shaft.

13. The combination of a single wire continuous multiple-helix spring comprising a 75 nested series of connected helices separated one from another to give clearance, winding means for said spring, and means automatically effective during the tensioning of the spring and before any helix contracts sufficiently to impinge upon the next inner 80 helix, for checking the winding operation.

14. In a spring motor, the combination of a spring comprising inner and outer helices, a revoluble core within the inner helix, means to wind the spring, means to hold 85 said core stationary during the winding of the spring, said core engageable and rotatable by the inner helix as the latter contacts upon winding thereof, and a stop brought into play by said core for arresting the winding 90 before the outer helix can contract sufficiently to grip the inner helix.

15. The combination with a revoluble 95 spring barrel, of a single wire continuous motor spring comprising helical coils nested one within another within said barrel, one end of said spring connected to said barrel to drive the same, a central shaft upon which said barrel is loosely mounted, the other end of said spring being connected to 100 said central shaft to enable the shaft to wind the spring, a stop mechanism normally ineffective to control said shaft, and means dependent upon the tensioned condition of the spring for bringing said stop mechanism 105 into play to stop said shaft before the coils contract sufficiently to grip one another.
